DESIGN FOR A COOK STOVE

Wilbur Henry Adams, Cleveland Heights, Ohio, assignor to Perfection Stove Company, Cleveland, Ohio, a corporation of Ohio

Application August 7, 1935, Serial No. 58,000

Term of patent 14 years

To all whom it may concern:

Be it known that I, Wilbur Henry Adams, a citizen of the United States, residing at Cleveland Heights, in the county of Cuyahoga and State of Ohio, have invented a new, original, and ornamental Design for Cook Stoves, of which the following is a specification, reference being had to the accompanying drawing, forming part hereof, and wherein Fig. 1 is a front elevation, and Fig. 2, a side elevation, of a cook stove showing my new design.

The dominant or characteristic feature of the design resides in the portions shown in full lines.

I claim:

The ornamental design for a cook stove as shown and described.

WILBUR HENRY ADAMS.
